CHAFING DISH

Daniel C. O'Connell, Bedford Village, N. Y., assignor to Sterno, Inc., New York, N. Y., a corporation of New York

Application November 6, 1952, Serial No. 22,155

Term of patent 14 years

(Cl. D44—15)

To all whom it may concern:

Be it known that I, Daniel C. O'Connell, a citizen of the United States, residing at Bedford Village, New York, have invented a new, original, and ornamental Design for a Chafing Dish, of which the following is a specification, reference being had to the accompanying drawing, forming part thereof, in which:

Fig. 1 is a perspective view of the chafing dish embodying my new design;

Fig. 2 is a top plan view thereof in which the broken lines representing the container have been omitted; and

Fig. 3 is an elevational detail, with parts broken away, of the top portion of the stand showing the horizontal groove in the upper part of the leg portion in relation to the annular band portion of the design.

The dominant features of the design reside in the portions shown in full lines.

I claim:

The ornamental design for a chafing dish, as shown and described.

DANIEL C. O'CONNELL.
